UNITED STATES PATENT OFFICE

172,703

RUG CUSHION OR SIMILAR ARTICLE

Wilson R. Bull, Ansonia, Conn., assignor to United States Rubber Company, New York, N. Y., a corporation of New Jersey

Application January 6, 1953, Serial No. 23,042

Term of patent 14 years

(Cl. D92—21)

To all whom it may concern:

Be it known that I, Wilson R. Bull, a citizen of the United States, residing at Ansonia, in the county of New Haven and State of Connecticut, have invented a new, original, and ornamental Design for a Rug Cushion or Similar Article, of which the following is a specification, reference being had to the accompanying drawing forming part thereof.

Fig. 1 is a top plan view of a rug cushion or similar article, showing my new design;

Fig. 2 is a bottom view of the rug cushion or similar article of Fig. 1;

Fig. 3 is a section taken on the line 3—3 of Fig. 1; and

Fig. 4 is a section taken on the line 4—4 of Fig. 1.

I claim:

The ornamental design for a rug cushion or similar article, as shown.
